UNITED STATES PATENT OFFICE.

CHARLES C. BLACKMORE, OF DAYTON, OHIO.

DESIGN FOR A RADIOCABINET.

Application filed February 12, 1925. Serial No. 12,364. Term of patent 14 years.

To all whom it may concern:

Be it known that I, CHARLES C. BLACKMORE, a citizen of the United States, residing at Dayton, in the county of Montgomery and State of Ohio, have invented a new, original, and ornamental Design for a Radiocabinet, of which the following is a specification, reference being had to the accompanying drawings, forming part thereof.

In the drawings:

Figure 1 is a front elevation of my cabinet showing my new design;
Figure 2 is a plan view of the same.

I claim:

The ornamental design for a radiocabinet, as shown.

CHARLES C. BLACKMORE.
